US0D1012294S

(12) **United States Design Patent** (10) Patent No.: **US D1,012,294 S**
(45) Date of Patent: ** Jan. 23, 2024

(54) **ELECTRODE PAD**

(71) Applicant: **Haifei Long**, Anhui (CN)

(72) Inventor: **Haifei Long**, Anhui (CN)

(**) Term: **15 Years**

(21) Appl. No.: **29/797,822**

(22) Filed: **Jul. 2, 2021**

(51) LOC (14) Cl. **24-02**

(52) U.S. Cl.

USPC **D24/187**

(57) **CLAIM**

The ornamental design for an electrode pad, as shown and described.

DESCRIPTION

FIG. 1 is a perspective view of an electrode pad showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

This product is used for human body electrical stimulation treatment.
